UNITED STATES PATENT OFFICE.

CHARLES A. HOFFMAN, OF MINNEAPOLIS, MINNESOTA.

EYEGLASS-MOUNTING.

960,642.

Specification of Letters Patent. Patented June 7, 1910.

Application filed October 19, 1907. Serial No. 398,290.

To all whom it may concern:

Be it known that I, CHARLES A. HOFFMAN, a citizen of the United States of America, residing at Minneapolis, in the county of 5 Hennepin and State of Minnesota, have invented new and useful Improvements in Eyeglass-Mountings, of which the following is a specification.

This invention relates to eye-glass mountings and consists in the construction and arrangement of devices hereinafter described and claimed.

One object of my invention is to provide means whereby the nose guards are pivotally 15 connected to the lens carrying post.

A further object is to combine with the pivotally mounted nose guards springs for pressing them against the nose of the wearer.

20 In the accompanying drawings,—Figure 1 is a top plan view of a pair of eye-glasses provided with my improved mountings. Fig. 2 is a central sectional view of the same. Fig. 3 is a detail top plan view of the same. 25 Fig. 4 is a sectional view of a modified construction of my improved eye-glass mounting. Fig. 5 is a detail sectional view taken on the plane intersecting one of the studs or posts. Fig. 6 is a detail top plan view of the 30 same.

Referring to the form of my invention shown in Figs. 1, 2 and 3 the bridge piece 1 is provided at its ends with downwardly extending portions 2 which enter openings 3 in boxes 4 at the inner ends of the studs or bolts 5 which may otherwise be of any suitable form and attached to the lenses 6 by any suitable means. The said boxes 4 are each formed at its inner side with a metallic 35 strip 7 which has a rearwardly bent double portion 8 providing a pivot eye 9, an outwardly extending arm 10 to close the outer side of the opening 3 and an outwardly bent arm 11 to bear against an arm 12 at the front 40 side of the said recess, the said arm 12 being shorter than the said arm 11, as shown in detail in Fig. 6. The depending portions 45 2 of the bridge piece bear against the inner sides of the recesses 3, and between the said portions 2 of the bridge piece and the arms 10 of the boxes are eyes 13 formed at the upper ends of the inner arms 14 of substantially U-shaped springs 15 which are here 50 shown as provided with spring coils 16 and 55 which connect the inner arms 14 and the outer arms 17 of such springs, said arms 17

extending upwardly to a greater height than the boxes 4, as shown in Fig. 2. Screws 18 pass through openings in the arms 10 and the bridge piece downturned portions 2 and 60 enter threaded openings in the posts or studs 5 and also pass through the eyes 13 of the springs 16. The arms 11 of the boxes being disconnected from and disposed in overlapping relation with reference to the arms 12 65 thereof enable the arms 10 of the boxes which form the inner sides of the openings or recesses 3 to be moved or adjusted by the screws 18 to enable the bridge piece portions 2 and the eye portions of the springs to be 70 firmly clamped in the openings or recesses in the boxes by the said screws, as will be understood by reference to Figs. 5 and 6 of the drawings.

Each nose guard or nose piece 19 is provided with an arm 20 which is bent to form a vertical pivot portion 21 which has its bearing in the pivot eye 9 of one of the boxes 4, the upper portion of the said arm projecting forwardly and upwardly from the said 75 pivot eye as shown in Figs. 1 and 2, and being engaged at a suitable distance from its front end by the upper portion of the arm 17 of one of the springs so that the tension of the said springs is exerted against said 80 arms of the nose pieces or guards to press the latter toward each other and thereby cause them to be pressed against opposite sides of the nose of the wearer by the tension of said springs to retain the glasses in place. 85

In the form of my invention shown in Figs. 3 and 4, each spring 22 has a free rear arm 23 which bears against the outer side of the arm 24 of the nose guard 25 so that the nose guards are pressed by the springs toward each other. 95

It will be understood that in the form of my invention shown in Figs. 1 to 4, inclusive, the forwardly and upwardly extending portions of the pivot arms of the nose guards 100 act as levers which enable the wearer to readily disengage the nose guards from his nose in order to adjust or remove the glasses.

I claim:

1. An eye glass comprising lenses, said 105 lenses having their mountings provided with boxes, said boxes having eyes formed therein, a nose bridge, said nose bridge having downwardly extending portions engaged in the said boxes, arms pivotally mounted on 110 said boxes and provided with downwardly extending movable nose guard carrying

arms, and springs mounted in said boxes and provided with upwardly extending arms adapted to yieldingly engage the said movable arms so that the nose guards will be forced toward each other to assume their operative or clamping positions.

2. An eye glass comprising lenses, said lenses having their mountings provided with boxes, said boxes having recesses formed 10 therein and provided rearwardly of the recesses with vertical eyes, arms extending forwardly of the boxes to form levers and provided with depending portions mounted in the eyes of the boxes, said arms being provided at their lower ends with guards or 15

nose engaging pieces, a bridge piece connecting the lenses and provided with eyes which are disposed in the recesses formed in the boxes, springs having portions disposed in the recesses formed in the boxes, and arms 20 carried by the spring adapted to be yieldingly engaged with the first named arms so that the nose guards or nose engaging pieces will be normally moved toward each other.

In testimony whereof I affix my signature 25 in presence of two witnesses.

CHARLES A. HOFFMAN.
